(57) **CLAIM**

The ornamental design for a siding installation apparatus, as shown and described.

DESCRIPTION

FIG. 1 is a front perspective view of a siding installation apparatus showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof, shown enlarged with respect to FIG. 1; and,

FIG. 8 is a bottom view thereof.

The broken lines illustrate portions of the siding installation apparatus that form no part of the claimed design.

1 Claim, 8 Drawing Sheets
